UNITED STATES PATENT OFFICE.

ALBERT W. GUSTAFSON, OF JERSEY CITY, NEW JERSEY.

KNOCKDOWN BOX.

1,177,513.

Specification of Letters Patent.

Patented Mar. 28, 1916.

Application filed June 5, 1915. Serial No. 32,355.

To all whom it may concern:

Be it known that I, ALBERT W. GUSTAFSON, a citizen of the United States, residing at Jersey City, in the county of Hudson and 5 State of New Jersey, have invented new and useful Improvements in Knockdown Boxes, of which the following is a specification.

This invention relates to knockdown boxes and it consists in the novel features 10 hereinafter described and claimed.

An object of the invention is to provide a box of simple and durable structure especially adapted to be used for holding crackers, small cakes and the like, the parts of the 15 box being so connected together that they may be disjointed and packed in small compass when desired.

With the above object in view the box includes a bottom panel having up-standing 20 flanges at its longitudinal edges and provided at its ends with inwardly disposed folds. Side panels are provided at their ends with inwardly disposed folds adapted to engage folds provided at the side edges 25 of end panels which in turn are provided at their lower ends with folds adapted to engage under the folds provided at the ends of the bottom panel.

In the accompanying drawing:—Figure 1 30 is a perspective view of the box, showing the parts thereof set up. Fig. 2 is a longitudinal sectional view of the same. Fig. 3 is a perspective view of the bottom panel of the box. Fig. 4 is a perspective view of one 35 of the side panels of the box. Fig. 5 is a similar view of one of the end panels of the box.

The box includes a bottom panel 1 which is provided along its longitudinal edges with 40 up-standing flanges 2, and having at its ends and above its upper sides inwardly disposed folds 3. The box structure also includes end panels 4 provided at their lower edges with folds 5, the lower portions of which are 45 adapted to engage under the folds 3 provided at the ends of the bottom panel 1 in a manner as best shown in Fig. 2 of the drawing. The end panels 4 are provided at their side edges with folds 6 which are disposed 50 in the corner portions of the box when the parts are set up in the position as shown in Fig. 1 of the drawing. The box structure

also includes side panels 7 provided at their ends with inwardly disposed folds 8 adapted to engage in the folds 6 of the side edges of 55 the end panels 4 when the parts of the box are in set up position.

To assemble the parts the folds 5 of the end panels 4 are engaged with the folds 3 at the ends of the bottom panel 1 and when 60 so engaged the end panels 4 are disposed approximately at a right angle to the plane in which the bottom panel 1 lies. The side panels 7 are then slipped down along the side edges of the end panels 4 whereby the 65 folds 8 of the side panels 7 are engaged with the folds 6 upon the end panels 4 in a manner as best shown in Fig. 1 of the drawing. Thus the parts of the box are locked together and a top of any desired pattern may 70 be applied to the same.

The material of which the panels are composed is preferably metal, such as tin or the like, although any kind of material may be used in the box structure. As shown in the 75 drawing, the panels are shown closed, but it is to be understood that these panels may be provided with openings, and if desired, transparencies may be placed over the openings, whereby the contents of the box may 80 be viewed from the exterior and at the same time the contents are protected against external dust and other foreign matter.

From the above description taken in conjunction with the accompanying drawing, 85 it will be seen that a box of simple design is provided and that the box may be economically manufactured, and when the parts are set up the contents of the box are practically hermetically sealed, therefore the box is 90 especially adapted for containing eatable articles, as for instance cakes or crackers.

Having described the invention, what is claimed is:—

A box structure comprising a bottom 95 panel provided along its longitudinal edges with up-standing flanges and having at its ends inwardly disposed folds, end panels having at their lower edges folds adapted to engage in the folds at the ends of the bottom 100 panel, said end panels being provided along their side edges with folds, the last mentioned folds occupying the corner portions of the box when the parts are set up, side

panels provided at their ends with folds adapted to engage the folds of the side edges of the end panels said side panels when in position upon the bottom panel of the box 5 having their lower portions located within the flanges at the longer edges of the bottom panel and in close proximity to the same.

In testimony whereof I affix my signature in presence of two witnesses.

ALBERT W. GUSTAFSON.
